C. G. CURTIS & R. L. LOVELL,
STEAM PRIME MOVER FOR MARINE PROPULSION,
APPLICATION FILED JAN. 20, 1912.

1,150,250.

Patented Aug. 17, 1915.

UNITED STATES PATENT OFFICE.

CHARLES G. CURTIS, OF NEW YORK, N. Y., AND RALPH L. LOVELL, OF QUINCY, MASSACHUSETTS; SAID LOVELL ASSIGNOR TO FORE RIVER SHIPBUILDING COMPANY, OF QUINCY, MASSACHUSETTS, A CORPORATION OF MASSACHUSETTS.

STEAM PRIME MOVER FOR MARINE PROPULSION.

1,150,250.

Specification of Letters Patent. Patented Aug. 17, 1915.

Application filed January 20, 1912. Serial No. 672,455.

To all whom it may concern:

Be it known that we, CHARLES G. CURTIS, a citizen of the United States, residing in the borough of Manhattan, city, county, and State of New York, and RALPH L. LOVELL, a citizen of the United States, residing at Quincy, in the county of Norfolk and State of Massachusetts, have invented a new and useful Improvement in Steam Prime Movers for Marine Propulsion, of which the following is a specification.

The object we have in view is to provide a steam prime mover for marine propulsion, in which the principal power is derived from steam turbines, which improved prime mover will give a high efficiency at low power and speed.

In carrying out our invention, we provide each propeller shaft of a twin screw installation with a steam turbine adapted to utilize the full expansion of the steam. These steam turbines are preferably of the type having initial impulse wheel stages, and under full power conditions, the steam passes through the turbines in parallel, and independently of each other. For lower power and speed, under which conditions the steam flow would be too small for efficient utilization in the full power turbines, there is provided upon one of the propeller shafts a high pressure cruising steam prime mover, which is preferably a compound reciprocating engine adapted to be coupled with, and uncoupled from the shaft by a suitable clutch, such engine being adapted to operate efficiently on the upper part of the steam expansion range with the reduced steam flow required for cruising conditions. The high pressure cruising prime mover, instead of being a reciprocating engine, may be a steam turbine connected by a clutch with the shaft, or permanently connected therewith, and having the necessary small steam passageways to efficiently utilize the upper

portion of the steam expansion range with the small volume of steam required for cruising. A steam connection is made from the exhaust of the high pressure cruising prime mover to the full power steam turbine on the other propeller shaft, so that under cruising conditions, the steam flow will pass through the high pressure cruising prime mover into the turbine on the other shaft,

in which the lower part of the steam expansion range will be utilized. In order to control the distribution of energy under low power conditions, between the cruising prime mover on the one shaft and the turbine on the other shaft, so that the two shafts will do substantially equal work, means are provided for varying the intermediate pressure so as to secure this result. The exhaust from the cruising prime mover, before it reaches the turbine on the other shaft, is connected with a manifold, from which a series of connections are made to different stages of the turbine. These connections are controlled by valves, so that the steam may be exhausted from the cruising prime mover into the turbine at different stages. As a further means for securing the proper distribution of pressure, the connection of the manifold to the first stage of the turbine is made with a series of nozzle sections controlled by valves, so that the nozzle area may be adjusted. As a still further provision for the same purpose, a valve controlled by-pass is provided around the second cylinder of the compound steam-engine, or around some of the lower stages of the cruising turbine, the opening of which will still further increase the intermediate pressure.

The invention is also applicable to a four-shaft arrangement, the two shafts on each side of the ship being provided with a power equipment similar to that of the two shafts of a twin-screw arrangement.

In the accompanying drawing, Figure 1 is a plan view in outline showing the two propeller shafts with their prime movers connected therewith; Fig. 2 is an outline plan of a cruising steam turbine which may be used in place of the cruising steam engine; and Fig. 3 is a sectional view showing the means for varying the area of the cruising nozzles on one of the main turbines.

The main turbines 1, 2 are mounted on the propeller shafts 3, 4. They have direct steam connections 5, 6 from the boiler, and exhaust at 7, 8. These steam turbines are adapted each to utilize the full expansion of the steam, under high power conditions, when the steam flows through them in parallel. Coupled to the shaft 3 by a clutch 9, is a compound reciprocating engine 10, which is a small power cruising engine.

Boiler steam is supplied to this engine through the pipe 11, and the exhaust therefrom is carried by a pipe 12 to a manifold 13, from which a number of connections 14 are made with the head of the turbine 2 and with the casing of that turbine at different stages. The connections 14 are provided with controlling valves 15. The connection from the manifold 13 to the head of the turbine 2 is made with a cruising nozzle 16 (Fig. 3), different sections of which are adapted to be closed off from the steam flow by means of valves 17. A valve-controlled by-pass 18 is also provided around the low pressure cylinder of the engine 10. By these several means, the intermediate pressure or that in the pipe 12 can be varied under the different conditions of power and speed, so as to distribute the energy with substantial equality between the cruising engine and the turbine. Under cruising conditions, the engine will be coupled with the shaft 3, and the steam will flow through the engine to the turbine 2, the turbine 1 being out of service. Under high power conditions, the engine will be uncoupled from the shaft, and the steam will be passed through the two main turbines in parallel. Instead of a cruising engine on the shaft 3, a cruising turbine 19 (Fig. 2) may be employed. This may be provided with a valve-controlled by-pass 20 around some of its lower stages, which bypass will be utilized to control the pressure distribution.

35. What we claim is:—

1. In a steam prime mover for marine propulsion, the combination of two full power steam turbines on separate shafts, a high pressure cruising steam prime mover on one shaft, means for passing steam directly to the full power turbines in parallel for high power and means for passing the steam in succession through the cruising prime mover on one shaft and the full power turbine on the other shaft for lower powers, substantially as set forth.

2. In a steam prime mover for marine propulsion, the combination of two full power turbines on separate shafts, a high pressure cruising reciprocating engine removably connected with one shaft, means for passing steam directly to the full power turbines in parallel for high power and means for passing the steam in succession through the reciprocating engine on one shaft and the full power turbine on the other shaft for lower powers, substantially as set forth.

3. In a steam prime mover for marine propulsion, the combination of two full power steam turbines on separate shafts, a high pressure cruising steam prime mover on one shaft, means for passing steam directly to the full power turbines in parallel for high power, means for passing the steam

in succession through the cruising prime mover on one shaft and the turbine on the other shaft for lower powers and means for controlling the distribution of energy between the cruising prime mover and the turbine so that the power will be divided approximately equal between the two shafts, substantially as set forth.

4. In a steam prime mover for marine propulsion, the combination of two full power steam turbines on separate shafts, a high pressure cruising steam prime mover on one shaft, means for passing steam directly to the full power turbines in parallel for high power, means for passing the steam in succession through the cruising prime mover on one shaft and the turbine on the other shaft for lower powers, the exhaust connections from the cruising prime mover to the turbine being made to different stages of the turbine, substantially as set forth.

5. In a steam prime mover for marine propulsion, the combination of two full power steam turbines on separate shafts, a high pressure cruising steam prime mover on one shaft, means for passing the steam directly to the full power turbines in parallel for high power, means for passing the steam in succession through the cruising prime mover on one shaft and the turbine on the other shaft for lower powers and an adjustable cruising nozzle on the turbine, substantially as set forth.

6. In a steam prime mover for marine propulsion, the combination of two full power steam turbines on separate shafts, a high pressure cruising steam prime mover on one shaft, means for passing the steam directly to the full power turbines in parallel for high power, means for passing the steam in succession through the cruising prime mover on one shaft and the turbine on the other shaft for lower powers and a bypass around the low pressure section of the cruising prime mover, substantially as set forth.

7. In a steam prime mover for marine propulsion, the combination with two shafts, of a high pressure steam prime mover on one shaft, and a steam turbine on the other shaft, a passage connecting the said two motor elements in succession, and controlling mechanism for controlling and varying the steam pressure in said passage, whereby an approximately equal division of power between the two shafts is produced, substantially as set forth.

8. In a steam prime mover for marine propulsion, the combination with two shafts, of a high pressure steam prime mover on one shaft, and a steam turbine on the other shaft, means for passing the steam in succession through the high pressure steam prime mover and the turbine, the exhaust connections from the high pressure steam

prime mover to the turbine being made to different stages of the turbine, substantially as set forth.

9. In a steam prime mover for marine propulsion, the combination with two shafts, of a high pressure steam prime mover on one shaft, and a steam turbine on the other shaft, means for passing the steam in succession through the high pressure steam prime mover and the turbine, and an adjustable cruising nozzle on the turbine, substantially as set forth.

10. In a steam prime mover for marine propulsion, the combination with two shafts, of a compound high pressure steam prime mover on one shaft, and a steam turbine on the other shaft, means for passing the steam

in succession through the high pressure steam prime mover and the turbine, and a by-pass around the low pressure section of the high pressure steam prime mover, substantially as set forth. 20
